Des. 179,255
Patented Nov. 20, 1950

179,255

PHONOGRAPH CABINET

Harry C. Kline, Jr., Buffalo, N. Y., assignor to Wendt-Squires, Inc., Cheektowaga, N. Y.

Application December 8, 1955, Serial No. 39,244

Term of patent 3½ years

(Cl. D56—4)

FIG. 1

FIG. 3

FIG. 2

FIG. 4

FIG. 5

Fig. 1 is a perspective view of a phonograph cabinet showing my new design;

Fig. 2 is a perspective view taken from the opposite side thereof;

Fig. 3 is a front elevational view thereof;

Fig. 4 is an end elevational view thereof; and

Fig. 5 is a top plan view thereof.

The dominant features of the design reside in the portions shown in full lines.

I claim:

The ornamental design for a phonograph cabinet, as shown and described.
